UNITED STATES PATENT OFFICE.

CHARLES B. DYER, OF INDIANAPOLIS, INDIANA.

DESIGN FOR AN EMBLEM, BADGE, BROOCH, PIN, CUFF BUTTON, WATCH FOB, OR
ARTICLE OF SIMILAR NATURE.

61,191.

Specification for Design.

Patented July 11, 1922.

Application filed March 27, 1922. Serial No. 1,421. Term of patent 14 years.

To all whom it may concern:

Be it known that I, CHARLES B. DYER, a citizen of the United States, residing at Indianapolis, Marion County, State of Indiana, have invented a new, original, and ornamental Design for Emblems, Badges, Brooches, Pins, Cuff Buttons, Watch Fobs, or Articles of Similar Nature, of which the following is a specification, reference being

had to the accompanying drawing, forming a part hereof.

The figure is a plan view of the button or pin embodying the design.

I claim:

The ornamental design for emblem, badge, brooch, pin, cuff button, watch fob, or article of similar nature, as shown.

CHARLES B. DYER.
